UNITED STATES PATENT OFFICE.

JOHN BLOCHER, OF WILLIAMSVILLE, NEW YORK.

CHAIN.

Specification of Letters Patent No. 30,797, dated December 4, 1860.

To all whom it may concern:

Be it known that I, JOHN BLOCHER, of 5
Williamsville, in the county of Erie and
State of New York, have invented a new
and useful Improvement in the Construction
of Chains; and I do hereby declare that
the following is a full, clear, and exact de- 10
scription of the same, reference being had
to the accompanying drawings, forming a
part of this specification, in which—

Figure 1 represents a side view. Fig. 2,
a front view, and Fig. 3, a central section
of the chain. Fig. 4 is a sectional view of
a single link, and Fig. 5 shows the chain
15 when applied to a drum.

Similar letters of reference in each of the
several figures indicate corresponding parts.

The nature of my invention consists in
the combination of the knee of one knife
20 edged link with the slot of another knife
edged link for the purpose of forming a
chain, the links of which cannot detach
themselves from each other.

To enable others, skilled in the art, to
25 make and use my invention, I will proceed
to describe its construction and operation.

The chain is formed of a succession of
links A, A', and B, B', the ends of each link
30 being bent in opposite directions as seen in
Figs. 1 and 3. The curved portion of each
link end represents a semi-circle. The
curved end of one link is hung into the
curved end of the next link and so on so
35 as to form a continuous chain.

The curved ends are all knife edged, as
seen at a, b. The edge of one link rests on the
hollow surface of the next link. The motion
40 of one link in relation to the next one
is the knife edge of the end of one of the
two links. This motion is attended with

very little friction, if any, and thus the
chain is made to possess a high degree of
flexibility. If the curved surface of the end
of one link were made to rest on and slide 45
in contact with the curved surface of the
other link, the two surfaces of a certain ex-
tent being in contact with and sliding upon
each other, would create considerable fric- 50
tion and correspondingly diminish the flexi-
bility of the chain.

To lock the links together so that they
cannot detach themselves from each other in
the line of the length of the chain and later-
ally to this line, a narrow knee D, D', is 55
riveted—at I—to the upper end of the
straight part of each link. One half of the
knee D, extends through a slot H, in the
upper end of the straight part of the link,
and fits into a corresponding slot C, in the 60
curved portion of the lower end of the next
link, as seen in Fig. 3, the knife edge B, of
the curved end B', of link B, being in con-
tact with the upper surface of the part D, of
the knee, whereby the two links are locked 65
together so that they cannot detach them-
selves from each other, without interfering
with the free motions of each link around the
fulcrum formed by the knife edges, as above
described. 70

What I claim as my invention and desire
to secure by Letters Patent, is—

The combination of the knee D, D', of one
knife edged link B, B', with a slot C, of
another knife edged link A, A', for the pur- 75
pose of forming a chain, the links of which
cannot detach themselves from each other,
substantially as set forth.

JOHN BLOCHER.
